[57] **CLAIM**

The ornamental design for a pump for transferring solid material and the like, as shown.

DESCRIPTION

FIG. 1 is a elevational view of a pump transferring solid material and the like showing my new design, the other side being a mirror image thereof;

FIG. 2 is a front elevational view thereof;

FIG. 3 is a rear elevational view thereof;

FIG. 4 is a top plan view thereof; and

FIG. 5 is a bottom plan view thereof.

Fig. 4

Fig. 5
